(57) **CLAIM**

The ornamental design for a work table support, as shown and described.

DESCRIPTION

FIG. 1 is a top isometric view of a work table support according to the present design;

FIG. 2 is a bottom isometric view thereof;

FIG. 3 is a rear end view thereof;

FIG. 4 is a front end view thereof;

FIG. 5 is a left side view thereof;

FIG. 6 is a right side view thereof;

FIG. 7 is a top view thereof; and,

FIG. 8 is a bottom view thereof.

In the drawings, the broken lines illustrate environment that forms no part of the claimed design.
